UNITED STATES PATENT OFFICE.

CHARLES H. MORGAN AND JOHN G. SNYDER, OF ALTOONA, PENNSYLVANIA.

RAILWAY-TIE FASTENING.

1,050,285.

Specification of Letters Patent. Patented Jan. 14, 1913.

Application filed May 11, 1911. Serial No. 626,582.

To all whom it may concern:

Be it known that we, CHARLES H. MORGAN and JOHN G. SNYDER, both citizens of the United States, and residents of Altoona, 5 in the county of Blair and State of Pennsylvania, have invented new and useful Improvements in Railway-Tie Fastenings, of which the following is a specification.

Our invention relates to the class of tie 10 fastenings which are employed in connection with steel ties and tie plates, and relates particularly to a means of securing the rail with a clip that is held by a bolt, which bolt is protected by a portion of the clip in 15 order to prevent breaking or bending of the same.

A further object of our invention is to make a compact adjustable tie fastening which will give the maximum strength with 20 the minimum amount of openings in the top of the tie or tie plate.

It also provides a means whereby the size of bolt needed for holding the clip can be reduced to approximately one-half of what 25 is ordinarily needed in the adjustable clips where the lateral pressure is against the bolt.

With this and other objects in view, our 30 invention consists of the combination and arrangement of parts shown in the accompanying drawing, in which—

Figure 1 is a perspective view of a steel tie showing the clip applied, and also showing the openings in the top of the tie which 35 are needed for securing the clip. Fig. 2 is a sectional view through the clip and portion of the tie, part of the same being shown in elevation. Fig. 3 is a sectional view of a different form of cover plate. Figs. 4, 5, 40 and 6 are bottom, top and end views of the same. Figs. 7, 8, 9 and 10 are similar views of a modified form of cover plate and locking plate. Figs. 11, 12 and 13 are plan and side views of the portion of the clip that 45 engages the base of the rail.

Similar letters and figures of reference refer to similar parts throughout the different figures of the drawing.

Our invention consists of a clip "9", as 50 shown in Fig. 11, which has its end "10" slightly raised to fit over the base of the rail, as shown in Figs. 1 and 2. This plate has an opening "11" with serrated edges "12". Into the opening "11" fits a locking 55 plate "6", which also has serrations on its ends, as shown at "13" Fig. 8. In this

figure the locking plate is denoted by "6". The serrations "13" are made to snugly fit the serrations "12", and the locking plate "6", or "6'" as the case may be, has an opening "5" through its center. This is to receive the bolt "15" that holds all of the parts together. This locking plate may be made in a separate piece, or integral with the cover plate "1" as is shown in Fig. 3. 60 When the locking plate "6", or "6'", is placed over the bolt, which has first been passed through the top of the tie or tie plate, into the keyhole slot "8", the clip "9" can be adjusted to the necessary 65 position for holding the base of the rail to gage, and put down over the locking plate which will fix its relative position thereto. Next in order is the cover plate "1", which, if separate from the locking 70 plate as shown in Fig. 7, is put over the bolt "15" through the opening "5" and the nut "16" screwed on the bolt. The cover plate "1" is provided with a depression "4" which is of sufficient depth to fully protect 75 the nut and upper end of the bolt. The cover plate "1" also has depending sides "2", which extend down over the edges of the clip "9" and fit snugly thereover. These depending sides "2" are of the same 80 length as the thickness of the plate "9". At the rear portion of these depending sides "2" are lugs "3", which extend downward from the sides "2" for a portion of their distance only, and are adapted to enter 85 openings "7" in the top of the tie or tie plate. These openings "7" are so placed relatively to the keyhole slots "8", that the distance from their rear ends, which are farthest from the base of the rail is exactly as far from the rear end of the keyhole slot "8" as the outer wall of the bolt hole "5" is from the rear end of the cover plate "1". The lugs "3" are made of such 90 size that their combined cross section is 95 equal to or slightly greater than the cross section of the bolt. 100

From this description it will readily be seen that when the parts are all in place and the nut screwed down, the lateral strain 105 upon the bolt will be at the center, and produced by the clip "9" on the serrations of the locking plate "6" or "6'", which in turn puts the strain on the bolt. By reason of the lugs "3" engaging openings in the tie, 110 and the lower end of the bolt engaging the end of the keyhole slot "8," and the upper

end passing through the bolt hole "5," it would require a double shear of the bolt in order to cause a break. It is, of course, understood that all parts upon which a lateral strain is put are of slightly larger cross section than the cross section of the bolt.

From Figs. 3 and 7 it is apparent that when the nut is screwed on the bolt, the cover plate "1," which has a rounded upper surface, will fully protect it from any blows caused by derailment of cars, or from any other lateral blows. If found necessary, a washer may be employed between the nut and the portion of the cover plate engaged thereby, but ordinarily this is not required because there is no play between the parts of the clip which would have a tendency to loosen the nut.

A further object of our invention is to modify the clip so that it can still be used on straight track without the adjustable feature. To do this we strike up lugs "14" from the clip "9" and put a bolt hole "17" in the clip "9" instead of the opening "11." This bolt hole and the lugs are in the same relative position as the bolt hole and lugs on the cover plate in the adjustable form of fastening. The cover plate, which we use in connection with this form of clip will not require the lugs "3," but will be substantially the same shape and structure as shown in Figs. 3 and 7, except that the lugs "3" are omitted. The same openings in the tie, or tie plate, are used as in the case of the adjustable clip, and in order to make an allowance for some adjustability, the outer clip is made about a quarter inch shorter than the inner clip. If the rail wears on the inside to the extent of a quarter of an inch, then it can readily be adjusted to gage by a mere reversal of the clips. If it does not wear to that extent it is not sufficient to do any harm and no readjustment is necessary.

It will also be seen by reference to Figs. 1 to 6 inclusive, that when the locking plate "6" is made integral with the cover plate "1," there is no shearing strain on the bolt "15," because all of the lateral strain due to the pressure of the base of the rail against the clip "9" is borne by the locking plate "6," and the lugs "3" projecting downward into the openings "7" prevent any shearing strain being put upon the bolt "15." The only requirement in this case to make the construction safe is that the combined cross sections of the serrations "13," shall be of such size as to effectually resist the shearing strain put upon the clip "9." When the locking plate "6," shown in Fig. 8, is separate from the cover plate "1," all of the shearing stress comes upon the bolt, but in this case it is altogether between the

ends, and the bolt would have to be sheared in two places before it would give way. For this reason the bolt need be only half the cross section that is used in other forms of clips where the strain is put upon the overhanging portion of the bolt.

We claim—

1. A railway tie fastening consisting of a plate having openings, a clip for engaging the base of the rail, a bolt to engage one of the openings in the plate, a cover plate, means intermediate the cover plate and clip for holding said clip in its adjusted position, and means on said cover plate coöperating with the first mentioned plate to secure the clip, substantially as described.

2. A railway tie, openings in the top of said tie, a clip for holding the base of the rail in place, a cover plate and bolt for holding the parts together, means for protecting the top of the bolt, and means for adjusting the rail to gage.

3. A railway tie, openings in the top of the tie, a bolt for engaging one of the openings, a clip for engaging the base of the rail, a cover plate, means on said cover plate for engaging the other openings in the top of the tie, and means integral with said cover plate and projecting below it coöperating with means on the clip to hold said clip in any adjusted position.

4. The combination of a tie, openings in the top of said tie, a bolt adapted to engage one of the openings, a clip, an opening in said clip having serrated edges, a cover plate with depending edges to engage the sides of the clip, lugs on said cover plate for engaging other openings in the top of the tie, a locking plate integral with the cover plate and adapted to engage the serrations in the opening of the clip, and means on the cover plate for protecting the top of the bolt.

5. The combination of the shell of a metal tie having openings in the top, a clip for engaging the base of the rail, a cover plate for the clip, a bolt, means intermediate the cover plate and clip and means for supporting both ends of the bolt so as to put the strain in the center.

6. The combination of a metal tie having openings in the top, a clip adapted to engage the base of the rail, a cover plate, a bolt for holding all of the parts together, and means on said cover plate coöperating with the clip for taking the shearing strain off the bolt.
